The ornamental design for a rotatable light, as shown and described.

DESCRIPTION

FIG. 1 is a top perspective view of the rotatable light showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing the grip bumps are for the purpose of illustrating environmental structure form no part of the claimed design.
